UNITED STATES PATENT OFFICE.

RICHARD EHLERS, OF SEATTLE, WASHINGTON, ASSIGNOR TO ARNOLD A. BARKEY, OF SEATTLE, WASHINGTON.

AIR-SUPPLY DEVICE FOR EXPLOSIVE-ENGINES.

1,273,837.

Specification of Letters Patent. Patented July 30, 1918.

Application filed August 15, 1916. Serial No. 114,976.

To all whom it may concern:

Be it known that I, RICHARD EHLERS, a citizen of the United States, residing at Seattle, in the county of King and State of Washington, have invented certain new and useful Improvements in Air-Supply Devices for Explosive-Engines, of which the following is a specification.

This invention relates to regulating valves which are employed for controlling the quantity of auxiliary air admitted into the gas supply pipe of an internal combustion engine; and its object is the perfecting of devices of this character.

The invention is illustrated in the accompany drawings, in which—

Figure 1 is a view in vertical longitudinal section of a regulating valve applied to the representation of an engine manifold connection. Fig. 2 is a horizontal sectional view taken through 2—2 of Fig. 1. Fig. 3 is a front elevational view of parts shown in Fig. 1. Fig. 4 is a fragmentary sectional view similar to Fig. 1 with the valve proper illustrated in its closed position.

In said drawings, the reference numeral 5 designates a casing having a chamber extending from its upper end to within a short distance of its lower end. The upper portion 6 of the casing chamber is desirably formed with a cylindrical peripheral wall which extends to a shoulder 7 and below the latter the chamber portion 8 is formed of a truncated conical shape.

Positioned within such tapering portion of the chamber is a disk valve 9 of a diameter equal to that of the chamber at or about the mid-height of the same.

10 represents a helical spring bearing upon the bottom 11 of the valve chamber and adapted to yieldingly support the valve 9 near the upper end of the chamber part 8. In the peripheral wall of the casing and communicating with the upper portion of the chamber is one or more air inlet openings 12, two being shown at diametrically opposite sides.

An outlet opening 13 is provided for the chamber below the elevation whereat the valve will seat against the chamber wall when the valve is drawn down in opposition to the spring 10, as will be hereinafter explained.

A nipple 14 formed with or screwed into a

threaded hole which communicates with the 55 opening 13 is utilized to connect the device with an ordinary manifold, indicated by 15, through which a mixture of combustible gases is transferred to the cylinders of an internal combustion engine from a carbureter, or an equivalent.

16 represents a cylindrical hollow plug or cock inserted within the upper portion 6 of the casing chamber. This plug is open at the bottom and has in its periphery apertures 17 adapted to register with the air inlet openings 12 when the plug is moved into one rotary position and to close the openings, more or less, when turned into other positions.

To effect rotary adjustments of the plug, I employ a finger 18 extending radially from the plug through a circumferentially arranged slot 19 provided in the casing. The slot 19 is desirably located and is of such 75 length that the plug handle or finger 18 will be stopped by the slot ends when the plug is rotated to present the apertures 17 in full open and closed relations, respectively, with the air inlet holes 12. The finger 18 is de- 80 tachably connected to the plug and serves to prevent the accidental withdrawal of the plug.

In the operation of the engine with which my invention is associated, there will be a 85 vacuum created in the manifold dependent upon the speed of the pistons and the amount of throttle opening. When this vacuum is relatively high, a suction will obtain in the communicating casing 5 which 90 tends to draw air from the outside through inlets 17, in the occurrence of which the valve 9 is drawn down in opposition to the spring 10.

Where such suction is sufficiently great 95 and prolonged, the valve will eventually be drawn into its lowermost position whereat it is arrested, as shown in Fig. 4, by lodging on the tapering wall of the chamber part 8. This will effect the stoppage of an air sup- 100 ply through the casing until the vacuum is reduced through the supply of a mixture of the combustible gas and air from the car- bureter.

The valve 9 is, however, seldom drawn 105 down into such passage-closing position, as the spring 10 will assert its increasing power as it is being contracted, and result in a de-

crease only of the air flow through the casing because, as the valve descends in the tapering chamber part, the annular space about the valve diminishes.

5 By thus providing means to decrease the air passage as the vacuum increases, and vice versa, it is apparent that the device serves to automatically furnish air, supplementary to that afforded by the carburetor, in quantities most suitable to an economical consumption of fuel and the efficiency of the engine.

10 It is a well-known fact that when the engine is running slow and developing little power, the vacuum is comparatively great and the engine should be supplied with a richer explosive mixture than is requisite when the engine speed and work is increased.

15 20 My improved devices accommodate themselves to such demands by arranging the spring-pressed valve with respect to the conical wall so that the air passage will decrease or increase in reverse proportions to the vacuum strength, so to speak, occurring in the manifold.

25 30 The function of the cock 16 is to enable the operator to render the automatic devices temporarily inoperative or at least lessen its capacity to supply air as, for example, when starting the engine in cold weather it is desirable to prevent the engine cylinders becoming unduly chilled.

35 35 After the engine has been in operation for a short while, the cock should be gradually turned into its open position, whereupon the regulating valve would respond to the demand.

Copies of this patent may be obtained for five cents each, by addressing the "Commissioner of Patents, Washington, D. C."

What I claim, is—

A device of the class described including 40 a hollow casing having one end opened, the interior of said casing having an upper cylindrical chamber and a conical chamber which tapers downwardly and inwardly from a point adjacent the open end to the 45 closed end thereof, said casing provided adjacent its open end with opposed inlet openings, a hollow plug rotatably mounted in the open end of said casing and provided with opposed openings adapted when rotated to be moved into and out of registration with the openings in the casing, means fastened to said plug and extending exteriorly of the said casing whereby said plug may be rotated, a spring located in said casing and having one end bearing against the closed end thereof, a disk valve connected to the other end of said spring and adapted to normally remain unseated, the diameter of the disk being greater than the interior 60 diameter of the lower part of the conical chamber and said casing having an outlet opening located between the closed end thereof, and the valve, whereby upon a 65 vacuum or suction being created in said casing through the last named opening the valve will be drawn downwardly against the wall of the casing to close communication between the inlet and outlet openings.

Signed at Seattle, Washington, this 70 day of August, 1916.

RICHARD EHLERS.
